HOISTING WHEEL

Roy H. Stein, 3920 Zephyr St.,
Wheat Ridge, Colo. 80033

Filed June 29, 1970, Ser. No. 23,749

Term of patent 14 years

Int. Cl. D8—05

U.S. Cl. D8—216

Fig. 1

Fig. 2

Fig. 3

Fig. 4

FIG. 1 is an elevational side view of a hoisting wheel showing my new design, the opposite side of the device being a mirror image of the side shown.

FIG. 2 is an elevational end view of the hoisting wheel shown in FIG. 1.

FIG. 3 is a top plan view of the hoisting wheel shown in FIG. 1.

FIG. 4 is a transverse sectional view in the plane of the line 4—4 of FIG. 1 showing the shape of the spokes of the wheel.

I claim:

The ornamental design for a hoisting wheel, substantially as shown and described.
